UNITED STATES PATENT OFFICE.

SAMUEL P. JACKSON, OF EAST LIVERPOOL, OHIO, ASSIGNOR TO HOMER LAUGHLIN, OF SAME PLACE.

MOLD OR OUTSIDE RING FOR POTTERY.

SPECIFICATION forming part of Letters Patent No. 406,350, dated July 2, 1889.

Application filed March 7, 1889. Serial No. 302,280. (No model.)

To all whom it may concern:

Be it known that I, SAMUEL P. JACKSON, a citizen of the United States of America, residing at East Liverpool, in the county of Columbia and State of Ohio, have invented certain new and useful Improvements in Molds or Outside Rings for Pottery; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in the manufacture of pottery, the object of my invention being to provide means which are adapted to be secured to the revolving head or disk of a pottery-lathe, comprising a ring, which is adapted to engage with a socket attached to the head of the lathe, so as to hold securely in place the mold upon which the article or dish is formed, as will be hereinafter fully set forth.

20 In the accompanying drawings, Figures 1 and 2 are sectional views taken through diametrically-opposite points, Fig. 1 showing the mold slightly elevated above the revolving head of the lathe. Fig. 3 is a plan view of the revolving head with a permanent ring attached thereto. Fig. 4 is a plan view of the removable ring. Fig. 5 is a sectional view of the same.

25 A refers to the whirling table or head of an oval lathe, which is rotated in the usual manner. This head has attached thereto a socket-bed B, the walls thereof being raised or tapered, and at a suitable point upon the exterior wall this socket-bed is provided with a projection b, and has also formed therewith extensions b', by means of which it is attached to the head A. The upper edge of this socket-bed has an indicating-notch b² formed in the same, the notch b² and projection b being of any suitable configuration.

30 C refers to a removable ring, which is constructed to fit snugly over the socket-bed B, and it may be provided with recesses c and c², which register with the projection b and

notch b² of the socket-bed. The base is cut away to provide space in which the projections b' of the socket-bed will lie.

It will be observed that the exterior walls of the socket-bed taper, and that the interior 55 walls of the ring C also taper, so that when the ring is placed on the socket-bed the parts will be immovably connected and will fit closely together. This is very desirable, especially where the parts are molded in plaster. 60

When the ring C is made of plaster, it may be provided with a metal band c'. At two diametrically-opposite points e the ring C is contracted or cut away, so that it will be of less diameter than the mold placed above the 65 same.

The mold D is preferably made of plaster, and the upper surface may be shaped to correspond with the interior configuration of a dish, while the under side is projected downwardly, the exterior wall of which is tapered to lie within the inclined walls of the socket-bed. The balance of the under surface beyond the projection is shaped to correspond with the upper surface of the socket-bed and 70 ring. The under side of the mold may have recesses or projections, which will register with the projections or recesses formed in the ring and socket-bed. 75

The parts hereinbefore described may be 80 made of any suitable material, as plaster, metal, or composition. The mold D is preferably made of plaster, while plaster is also preferred for the ring C.

It will be understood that the mold D is of 85 proper shape to construct the article desired thereon, and that after the outside of the dish, plate, or other object has been formed the mold and ware are removed to the drying-room. The shape of the mold is immaterial, 90 as well as the shape of the ring and socket-bed, and the oval form is shown merely for the purpose of illustration, as it is the preferred form and one adapted to be used in connection with an oval lathe or jigger. 95

The ring C is cut away at e, so that the ends of the mold may be readily grasped by the attendant in removing the same from the socket-bed.

In manufacturing different styles or sizes of 100

dishes or pottery-ware different sizes of rings C and molds D can be used upon the same head or parts A and B, and the parts are so constructed that when they are placed together they are practically immovable, thereby producing pottery-ware much more uniform and with greater facility.

By means of the hereinbefore-described device the permanently-attached head or ring 10 is dispensed with, and several sizes of dishes can be made upon one machine without destroying or changing the permanent head or ring A and B.

Having thus described my invention, what I 15 claim as new, and desire to secure by Letters Patent, is—

1. In combination with a lathe head or table, a socket-bed attached thereto and provided with raised walls, a removable ring adapted 20 to encircle the socket-bed and form a continuation thereof, and a mold constructed to have

a bearing in and on the socket-bed and upon the removable ring, substantially as shown, and for the purpose set forth.

2. In combination with a head or rotary 25 disk A, having a socket-bed attached thereto, a removable ring C, having interior wall adapted to fit over the exterior wall of the socket-bed, said ring being cut away at opposite points to be of less diameter than the mold, 30 and a mold D, having the base shaped to fit within the inner walls of the socket-bed and also bear upon the upper faces of said socket-bed and ring, substantially as shown, and for the purpose set forth.

In testimony whereof I affix my signature in presence of two witnesses.

SAMUEL P. JACKSON.
